UNITED STATES PATENT OFFICE.

TRUE M. AVERY, OF GLENS FALLS, NEW YORK, ASSIGNOR TO ARROW-GRIP MANUFACTURING CO. INC., OF GLENS FALLS, NEW YORK, A CORPORATION OF NEW YORK.

NONSKID DEVICE.

1,409,643.

Specification of Letters Patent. Patented Mar. 14, 1922.

Application filed June 4, 1919. Serial No. 301,622.

To all whom it may concern:

Be it known that I, TRUE M. AVERY, a citizen of the United States, residing at Glens Falls, in the county of Warren and 5 State of New York, have invented new and useful Improvements in Nonskid Devices, of which the following is a specification.

This invention relates to improvements in non-skid devices for vehicle wheels, proposing 10 a device which is intended to secure the non-skid element, i. e. the cross chain, in anchored relation and which is especially applicable to so-called "steel" wheels, that is to say, wheels which are without spokes 15 and whose structure includes disc-like side plates to which the hub and felly are secured.

The principal objects of the invention, briefly stated, are to provide a non-skid device 20 for use as described which may be manipulated with quickness and facility in putting on or taking off the non-skid element, which effects the certain and reliable securing of said element and whose parts 25 for the securing of said element take up a minimum degree of space at the sides of the wheel.

With the above objects in view the invention 30 consists in certain novel features of structure and relation appertaining to the combination of two hook parts for arrangement at opposite sides of the wheel to secure the terminal links or eyes of the non-skid element and also in certain novel features 35 of the structure of one of said hook parts, all of which features will be pointed out as the description proceeds.

An embodiment of the invention is illustrated in the accompanying drawings, 40 wherein:

Figure 1 is a cross-sectional view showing a non-skid device in accordance with the present invention in its application to a disc wheel, the cooperating hook part being 45 shown in side elevation.

Figure 2 is a side elevation of one of the hook parts with the movable guard or closure shown in section.

Figure 3 is a front elevation of the same. 50 Figure 4 is a front elevation of the companion cooperating hook part.

Similar characters of reference designate corresponding parts throughout the several views.

55 The improved device consists of two companion elements 1 and 2 for attachment to

the wheel at its opposite sides. The invention is applicable to so-called "steel" wheels of various constructions and which embody annular side plates A and B connected to the hub and the felly. Figure 1 shows these side plates as provided with shoulders C of angular cross-section which may be formed at regular intervals and which have perpendicular walls D; and in the construction disclosed the elements 1 and 2 are secured to the walls D.

Each of the companion elements includes a flat base 3 provided with apertured terminal ears 4 for its attachment to the wall D. 70 Any suitable fastening means may be employed for the attachment of the elements 1 and 2, for example, fastening bolts 5 which extend transversely through the wheel and are common to each pair of cooperating elements. The elements 1 and 2 are provided with single hooks, 6 and 7 respectively.

These hooks are located centrally of the bases 3 and project laterally from said bases in planes transverse to the wheel. According 80 to the invention, the hook 6 cooperates with a movable guard or closure 8 while the hook 7 is devoid of a movable guard or closure but is recurvate, that is to say, its terminal 85 9 is directed back or inward toward the base 3, an open chain link passage being left between said terminal and base. In the construction preferred, the hook 6 is devoid of recurvate formation, that is to say, its terminal portion is presented perpendicularly;

90 and the chain link passage between the terminal of the hook 6 and the base 3 is normally closed by the guard 8. The guard 8 may be of any suitable construction for the purposes in view, but it is preferably similar in general respects to the construction shown in my copending application Serial No. 147,856 and is so disclosed. As shown, said guard consists of a sheet metal part of channel cross-section provided with laterally 100 arranged resilient terminal lips 10 for frictional engagement with a cooperating lug 11 provided on the base 3. The lug 11 is preferably of round cross-section and is of greater diameter than the normal spacing 105

between the lips 10 whereby said lips may be sprung past the portion of said lug of greatest diameter and will thereafter press inward on the lug. The guard 8 is pivotally mounted at its end remote from the lips 10 110 upon a supporting lug 12 and is, therefore, movable to a position wherein it closes the

link passage between the hook 6 and the base 3 and its lips 10 are frictionally engaged with the lug 11 to secure the guard in such position or to a position wherein the 5 said link passage is open and the terminal link may be freely disengaged from the hook 6.

In the construction disclosed and with reference to certain specific details comprehended within the invention, the base 3 of the element 1 is provided centrally of its upper side with an inwardly directed projection 13 upon which the lug 12 is formed, said lug being upright from said projection 15 and the latter overhanging the shoulder C; and the guard 8 is arranged whereby in its closed position it projects laterally over the hook 6, preferably at a slight downward inclination, and in its open position it projects upright or substantially upright from the part 13. The part 13 may be formed at its sides with shoulders 14 which, when the guard 8 resumes its closed position, are engaged by the side portions 15 of said guard 25 and are thereby effective to limit its downward or closing movement. The free end of the guard 8 is preferably of open construction, as shown in Figures 2 and 3, so that when the guard is closed, a clearance or 30 opening 16 is provided which is utilized in connection with the opening of the guard. Thus, a screw driver or any suitable implement may be inserted through the opening 16 and with its end held in the angle formed by 35 the lug 12 with the upper face of the projection 13 may be manipulated against the upper or connecting wall of the guard 8 to raise said guard sufficiently to disengage the lips 10 from the lug 11.

40 The non-skid element, i. e. the cross chain E, is anchored to the wheel by means of the hooks 6 and 7 with which its terminal links are engaged. To secure the cross chain its terminal link at one end is engaged with 45 the hook 7 and, the guard 8 being in open position, its link at the other end is engaged with the hook 6, after which the guard 8 is moved to its closed position, its lips 10 snapping over the lug 11 and cooperating therewith to hold the guard closed. To remove 50 the cross chain the guard 8 is raised and the terminal links are disengaged successively from the hooks 6 and 7.

The arrangement of the guard 8 whereby, 55 when closed, it projects laterally over the hook 6 is of advantage from the standpoint of accessibility in connection with the manipulation of the guard; and in connection with such arrangement of the guard 8 60 the lug 11 is also arranged to overhang the hook and to project slightly below the guard. As thus arranged the lug 11 will provide a rigid abutment against which the 65 terminal link will exert thrust under some condition of its forcible displacement that

may be encountered in use, i. e., during the normal rotation of the wheel; and in this way the lug 11 protects the guard 8 from any pressure which might result in its accidental opening.

70

The perpendicular relation of the terminal portion of the hook 6 promotes facility in securing and removing the cross chain while the reliability of the securement of the cross chain is provided for by the positive 75 closure of the hook 6, as by the guard 8, and by the recurvate form of the hook 7, the overhanging relation of the terminal 9 preventing the accidental disengagement of the link which is secured by the hook 7.

80

As shown and preferred the element 1, which has the guard 8 is arranged at the outer side of the wheel where there are no obstructions and where the guard may be manipulated with facility and the element 85 2 is arranged at the inner side of the wheel where the presence of obstructions, such as the brake drum F, does not involve any problem, owing to said element being devoid of a guard or of movable parts.

90

I claim:

1. In a non-skid device for vehicle wheels, a chain-link-securing part comprising an attachment base and a single hook projecting laterally therefrom with a link passage between said base and the terminal of said hook, a pivoted guard to close said link passage and movable in a common plane with said hook and a lug projecting from said base in overhanging relation to said hook for frictional securing co-operation with said guard when the latter is in position to close said link passage, said lug projecting beyond the guard, when closed, toward the base of said hook.

100

2. In a non-skid device for vehicle wheels, a chain-link-securing part comprising an attachment base and a single hook projecting laterally therefrom with a link passage between said base and the terminal of said hook, said base having a projection along its edge and from its side opposite to the edge and side from which said hook projects, an upright lug on said projection, a second lug projecting from said base in overhanging relation to said hook, and a guard pivoted to said upright lug and movable in a common plane with said hook into overhanging relation to said hook to close said link passage, said guard near its outer end 110 having secured cooperation with said second lug.

115

In testimony whereof I have hereunto set my hand in presence of two subscribing witnesses.
